UNITED STATES PATENT OFFICE.

HENRY O. KUHLHOFF, OF EUCLID, OHIO, ASSIGNOR TO THE CONTINENTAL PRODUCTS COMPANY, OF CLEVELAND, OHIO, A CORPORATION OF OHIO.

PAINTING MACHINE.

Application filed October 9, 1925. Serial No. 61,455.

This invention as indicated relates to painting machines. More particularly, it comprises an apparatus adapted especially for placing zone marks upon paving to serve as guides for traffic. In view of the long distance over which it is frequently necessary to mark traffic lanes, the use of hand marking devices is found to be too slow a process and it is also one involving considerable danger for the persons using same.

The principal object of the present invention is to provide an improved type of marking apparatus which will be simple and economical in construction and more effective in operation than such structures heretofore in use.

Another object of the invention is to provide a distributing wheel within the paint reservoir which will serve to apply an even coat of paint to the applicator belt preliminary to the contacting of said belt with the road surface.

A further object of the invention is to provide for the application of pressure to the applicator belt, the belt itself not being under sufficient tension to be self driven and thus forming in effect an endless track laid down in front of the pressure rollers.

Another object of the invention is to drive the paint applying roller at the belt speed when the belt is moved through contact with the road surface.

Other and further objects of the invention will appear in the course of the following description. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:—

Fig. 1 is a top plan view of an apparatus embodying the principles of the invention, and Fig. 2 is a side elevation thereof.

As is clearly shown in the drawing, the apparatus comprises a frame 1 formed of a pair of side bars 2 provided with journals 3 at the forward ends to receive the axle 4 upon which the large drive wheels 5 of the

apparatus are engaged. The rearward end 55 of said frame is completed by means of a cross member 6 upon the upper side of which a tank 7 of rectangular outline is supported. A vertical standard 8 is secured to each side frame member at approximately its mid-length and is secured to the tank adjacent its upper end. Each of said vertical members extends above the tank a short distance for a purpose which will be presently described. Beneath the rearward portion of the frame, a plurality of small rollers 9 are provided, said rollers taking the principal weight of the paint reservoir. The tank is open at the top and the forward wall thereof is cut out adjacent its upper edge to permit the passage of the applicator belt 11 through a portion of the tank. Within the tank is provided a paint wheel or roller 12, said roller being adapted to have peripheral contact with the applicator belt within and adjacent the upper forward portion of the tank.

The applicator belt is preferably supported upon a plurality of wheels, the upper wheel 13 being carried in a U shaped bracket 14 which is pivotally mounted on the upper ends of the vertical standards 8 by means of pivots 15. At the rearward end of the U shaped bracket, an extension plate 16 is provided which is received beneath a U shaped bracket 17 secured to the upper side edges of the tank by means of bolts 18 or other suitable fastenings. An adjustment screw 19 is adapted to be engaged through a threaded opening 21 provided centrally of said U shaped bar. The adjustment screw has a handle portion at right angles to the body portion thereof and the lower end of said screw bears against the extension plate 16. Thus by turning the handle, the position of the wheel 13 may be varied and the tension on the applicator belt changed proportionately. This adjustment also controls the degree of contact with the paint wheel 12, and the thickness of the coat of paint applied to the belt may be modified accordingly.

The lower portion of the applicator belt extends about a pair of wheels or rollers 22 and 23 which are supported upon a pair of bracket arms 24, 25.

The bracket arm 24 comprises an elongated body portion provided with journals for said wheels at either end and with an

upwardly extending arm adjacent its rearward end. A journal 26 is provided at the upper end of said arm, said journal engaging over the axle for the large drive wheels. 5 The bracket 25 corresponds approximately in shape with the bracket 24 but in addition has an upwardly extending arm 27 provided with an opening adapted to be engaged by the lower end of a bent rod 28 which is secured at its upper end to the belt lifting lever 29 pivotally mounted upon a stud 31 secured to the upper side portion of the tank. The lever 29 is provided with an outwardly extending handle 32 and at an intermediate 10 point has an extension 33 formed integrally therewith which is provided at its forward end with a plurality of apertures 34 to receive one end of a cross bar 35. The opposite end of the cross bar is secured to the 15 end of a supporting arm 36, the forward end of which is similarly provided with a plurality of apertures 34. The supporting arm is curved to provide clearance over the shaft 37 upon which the upper belt supporting wheel is mounted. The rearward end of the arm 36 is pivotally mounted upon a stud 38 secured to the side of the tank in a position corresponding to that of the stud 31 heretofore described. The lever 29 when 20 drawn rearwardly is adapted to latch behind the spring catch 30.

The bracket arms 24, 25 are preferably secured together by a brace rod 41 and the bracket arm 25 is bent outwardly to position 25 the applicator belt slightly to one side of the central longitudinal line of the apparatus. Upon the axle 4, a large sprocket wheel 42 is mounted and a smaller sprocket wheel 43 is mounted upon the axle 44 of the forward 30 belt supporting roller 22. A sprocket chain 45 is engaged upon the sprocket wheels and thus the motion of the drive wheels is communicated to the forward applicator belt wheel 22 and the peripheral speed of said 35 wheels is thus made uniform and positive. At the outer end of the shaft 46 to which is secured the paint wheel 12, there is mounted a pulley 47 which is connected by means of a reversed belt 48 with a drive pulley 49 secured to the shaft 37 of the upper roller 13.

In order to move the apparatus along the road surface, a handle 51 is provided, said handle having a cross bar 52 at its upper end. At its lower end said handle is preferably secured to the right hand side frame member by means of a securing bracket 53. A drain plug 55 may be provided at one side of the tank.

The operation of the apparatus it is believed will be clear from the above description. The paint or other coating material employed in the apparatus is transferred from the periphery of the paint wheel as it is rotated to the under side of the applicator belt which then moves upwardly over the

roller 13 and downwardly over the roller 22 into contact with the road surface. The return movement of said applicator belt is over the small roller 23 which provides for an extended area of contact of said belt with 70 the road surface.

Under normal operative conditions just sufficient tension is applied to the belt to hold the same in light frictional contact with the rollers. Such tension may be varied by 75 means of the adjusting screw 19 which through its associated mechanism will raise or lower the position of the shaft 37 of the upper roller 13.

When the lever 29 is moved rearwardly, 80 the extension 33 thereof will be moved in an upward direction and the rod 35 supported thereon and upon the arm 36 will be brought into contact with the under side of the applicator belt. At the same time, 85 through the action of the bent rod 28, the rollers 22 and 23 will be moved forwardly and the tension on the belt will be relieved as well as its contact with the road surface. The degree of contact of the rod 35 with the under side of the applicator belt may be readily adjusted by means of the series of holes 34 at the forward ends of the members 33 and 36.

Where the belt is in contact with the road 90 surface, the rollers 22 and 23 will apply pressure to the inner surface of the applicator belt and will produce a satisfactory transfer of the paint on the outer surface thereof to the surface of the paving.

The position of the rollers 22 and 23 is automatically maintained by reason of the fact that the rearmost roller 23 moves slightly past a vertical line through the drive 100 wheel axle.

While reference has been made to a "paint 105 reservoir" and "paint", it is to be understood that any liquid mixture or compound suitable for the purpose may be used with the apparatus.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention.

1. An apparatus of the character described, having in combination a wheeled structure, a paint reservoir mounted thereon, an applicator belt supported in front of said paint reservoir, and means within said reservoir for applying paint solely to the outer surface of said belt.

2. An apparatus of the character described having in combination a wheel structure, a paint reservoir mounted thereon, a wheel supported adjacent the upper edge of said

reservoir, an applicator belt engaged over said wheel, means for supporting said applicator belt in contact with the surface to be marked, and means within said reservoir for applying paint solely to the outer surface of said applicator belt.

3. An apparatus of the character described having in combination a wheeled structure, a paint reservoir mounted thereon, a wheel 10 adjustably supported adjacent the upper edge of said reservoir, an applicator belt engaged over said wheel, means for supporting said applicator belt in contact with the surface to be marked, and means within said reservoir for applying paint solely to the outer surface of said applicator belt.

4. An apparatus of the character described having in combination a wheeled structure, a paint reservoir mounted thereon, an adjustable wheel supported adjacent the upper edge of said reservoir, an applicator belt engaged over said wheel, means for supporting said applicator belt in contact with the surface to be marked, and means within said reservoir for applying paint solely to the outer surface of said applicator belt.

5. An apparatus of the character described having in combination a wheeled structure, 30 a paint reservoir mounted thereon, a wheel mounted in a pivotally supported bracket adjacent to the forward upper edge of said reservoir, an applicator belt engaged over said wheel, means for adjusting the position of said bracket, and means within said reservoir for applying paint solely to the outer surface of said applicator belt.

6. An apparatus of the character described having in combination a wheeled structure, 40 a paint reservoir mounted thereon, a wheel mounted in a pivotally supported bracket adjacent to the forward upper edge of said reservoir, an applicator belt engaged over said wheel, an adjusting screw for controlling the position of said bracket, and means within said reservoir for applying paint solely to the outer surface of said applicator belt.

7. An apparatus of the character described 50 having in combination a wheeled structure, a paint reservoir mounted thereon, a wheel supported adjacent the upper edge of said reservoir, an applicator belt engaged thereon, a pair of wheels for supporting said applicator belt in contact with the surface to be marked, and means within said reservoir for applying paint to the outer surface of said applicator belt.

8. An apparatus of the character described 60 having in combination a wheeled structure, a paint reservoir thereon, a wheel support adjacent the upper edge of said reservoir, an applicator belt engaged thereon a pair of wheels for holding said applicator belt in contact with the surface to be marked, and

means within said reservoir for applying paint to the outer surface of said applicator belt.

9. An apparatus of the character described having in combination a wheeled structure, 70 a paint reservoir mounted thereon, a wheel support adjacent to upper edge of said reservoir, an applicator belt engaged over said wheel, means for supporting said applicator belt in contact with the surface to be marked, and a paint wheel within said reservoir for applying paint to the outer surface of said applicator belt.

10. An apparatus of the character described having in combination a wheeled structure, 80 a paint reservoir mounted thereon, a wheel support adjacent to upper edge of said reservoir, an applicator belt engaged over said wheel, means for supporting said applicator belt in contact with the surface to be marked, and a paint wheel immersed in said reservoir and bearing against said applicator belt while in contact with said upper supporting wheel for applying paint to the outer surface of said applicator belt.

11. An apparatus of the character described having in combination a wheeled structure, a paint reservoir mounted thereon, a wheel supported adjacent to the upper edge of said reservoir, an applicator belt engaged over said wheel, means for supporting said applicator belt in contact with the surface to be marked, a paint wheel immersed in said reservoir, and means independent of said belt contact for driving said paint wheel.

12. An apparatus of the character described having in combination a wheeled structure, a paint reservoir mounted thereon, a wheel supported adjacent to the upper forward portion of said reservoir, an applicator belt engaged over said upper wheel, means for supporting said applicator belt in contact with the surface to be marked, means within said reservoir for applying paint to the outer surface of said applicator belt, and means for simultaneously lifting said belt from contact with the surface to be marked and away from the upper belt supporting wheel.

13. An apparatus of the character described having in combination a wheeled structure, a paint reservoir mounted thereon, a wheel supported adjacent to the upper forward portion of said reservoir, an applicator belt engaged over said upper wheel, a wheel for supporting said applicator belt in contact with the surface to be marked, a wheel within said reservoir for applying paint to the outer surface of said applicator belt, and a lever for simultaneously lifting said belt 115 from contact with the surface to be marked and away from the upper belt supporting wheel.

14. An apparatus of the character described having in combination a wheeled 120

- structure, a paint reservoir mounted thereon, a wheel supported adjacent to the upper forward portion of said reservoir, an applicator belt engaged over said upper wheel, 5 means for supporting said applicator belt in contact with the surface to be marked, means within said reservoir for applying paint to the outer surface of said applicator belt, a belt lifter bar disposed beneath said applicator belt, pivotal supports for said bar having a plurality of adjustment apertures for the same, and means to move said bar and its supports to lift said belt away from the upper belt supporting wheel.
15. In apparatus of the character described, having in combination a wheeled structure, a paint-conveying belt, means for supporting said belt adjacent a source of paint supply, and rotating means for transferring paint from said source of paint supply solely to the outer surface of said conveying belt.
16. In apparatus of the character described, having in combination a wheeled 25 structure, a movable road contacting belt carried thereby, and rotating means for transferring paint solely to the contact surface of said belt.
17. In apparatus of the character described, having in combination a wheeled 30

structure, a movable road contacting belt carried thereby, a paint reservoir, and a paint roller adapted to dip into the paint in said reservoir and transfer the same to the contact surface of said belt.

35

18. In an apparatus of the character described, having in combination a wheeled structure, a movable road contacting belt carried thereby, means for transferring the paint to the contact surface only of said belt, and means for controlling the amount of paint transferred to said contact surface.

40

19. In an apparatus of the character described, the combination of a supporting structure adapted to be moved along a road surface, a paint reservoir carried thereby, a belt for carrying paint from said reservoir to said road surface and means for transferring paint solely to the outer surface of said belt from said reservoir and controlling the quantity of paint so transferred.

45

20. A paint conveying and distributing device for a painting machine, comprising a paint-conveying belt, means for transferring paint solely to the outer surface thereof, and means for controlling the thickness of the coat of paint applied to said belt.

50

Signed by me this 5th day of October, 1925.

HENRY O. KUHLHOFF.
